UNITED STATES PATENT OFFICE.

HANS LUDWIG OCHSNER, OF ALPENA, MICHIGAN, ASSIGNOR OF ONE-THIRD TO NELSON
M. EDDY, OF ALPENA, MICHIGAN.

WOMAN'S WORK AND SPORT GARMENT.

1,265,492.

Specification of Letters Patent.

Patented May 7, 1918.

Application filed October 3, 1917. Serial No. 194,528.

To all whom it may concern:

Be it known that I, HANS LUDWIG OCHSNER, a citizen of the United States, and a resident of Alpena, in the county of Alpena 5 and State of Michigan, have invented certain new and useful Improvements in Women's Work and Sport Garments, of which the following is a specification.

My present invention relates generally to 10 women's garments and more particularly to women's overgarments, my invention residing in a skirt or skirt portion of a dress to be worn with bloomers, my object being the provision of a skirt arrangement of such 15 a nature that its sections may be folded readily and quickly when desired to expose the bloomers when engaged in house-work, gardening, sports and the like.

In carrying out my invention I provide 20 a skirt or the skirt portion of a dress to be worn over bloomers, in front and rear sections, having side slits extending upwardly from the lower edge thereof, to a point adjacent to the hips, the slit portion being normally closed by connecting tabs, and the sections; which may be either integral or connected at points above the upper inner ends of the slits, being independently foldable around the hips so that the normally 25 concealed bloomers will be exposed and free use of the limbs permitted. In this latter or folded position of the skirt the connecting tabs before mentioned perform an additional function in connecting the ends of 30 each of the folded sections, the rear section being preferably folded first and connected at the front, and the front section being folded and connected at the rear, means being provided whereby to close the folded 35 front section at points adjacent the hips, so as to constitute an enlarged pocket across the front portion of the body of the wearer, capable of utilization as a clothes pin pocket or for the retention of such other articles of 40 like nature as may be desirable.

In its specific aspect my invention resides in the features of construction, arrangement and operation to be now described with respect to the accompanying drawing, forming 45 a part of this specification, and wherein:—

Figure 1 is a front elevation illustrating my improvements in their normal position with the skirt extended;

Fig. 2 is a similar view illustrating the 50 initial folding of the rear section prepara-

tory to its extension forwardly around the hips;

Fig. 3 is a similar view with the rear section folded and connected at the front;

Fig. 4 is a similar view illustrating the 60 initial folding of the front section preparatory to extension rearwardly around the hips;

Fig. 5 is a similar view illustrating the 65 front section folded and connected;

Fig. 6 is a rear elevation with the skirt in folded position, as seen in Fig. 5;

Fig. 7 is a view partly in elevation and in section through the folded skirt;

Fig. 8 is a side view of the lower portion 70 of the skirt in normally extended position;

Fig. 9 is a horizontal section taken there-through, substantially on line 9—9 of Fig. 8;

Fig. 10 is an inner face view of the rear 75 section of the skirt;

Fig. 11 is a similar view of the front section of the skirt, and,

Fig. 12 is a side view of the lower portion 80 of the skirt in extended position with the connecting tab released.

Referring now to these figures, my invention contemplates the provision of a woman's garment, and is directed particularly to the skirt portion which my invention contemplates forming in front and rear sections 85 15 and 16, and which I propose to provide with vertical side slits 17 extending upwardly from the lower edge of the skirt to points somewhat below the hips.

At opposite sides of the slits 17, the front 90 and rear sections are provided with horizontally aligned buttons 18, providing for their normal connection by means of tabs 19 adapted to extend across and bridge the slits 17, the said buttons and tabs being in 95 their normal positions located approximately midway of the length of the slits 17, as may be plainly seen by an inspection of Fig. 1.

The adjacent edges of the front and rear 100 sections 15 and 16 are preferably connected at points between the buttons 18 and the upper inner ends of the slits 17, by means of enlarged triangular webs 20 which are thus concealed in the normal extended position 105 of the garment with the tabs 19 in the position shown in Fig. 1, and which provide for certain conveniences in the folded position of the skirt sections as hereinafter described.

The skirt thus generally described may be either separate from the remainder or waist section 21 of the outer garments, or may be integral or connected thereto, and 5 worn with a belt 22, or as desired, the skirt provided by my invention being, however, particularly adapted to be worn with bloomers 23 of any suitable construction, as for instance, of the type shown in Figs. 4 to 7 10 inclusive, the purpose in view being the ready and quick folding of the skirt from its normal position covering and concealing the bloomers to a position where the bloomers will be exposed and free use of the limbs 15 of the wearer permitted as an assistance in house-work, sports and the like.

It is obvious that with these features in mind the skirt will be formed of various materials suitable for the particular purpose for which it is worn, bearing in mind 20 of course its adaptability to ready and quick folding, and just as quick and ready releasing to normal extended position after the purposes of its folding have been served.

25 In folding the garment as proposed by my invention the rear section is grasped at a point intermediate the ends of the slits 17 after the tabs 19 have been released and the grasped portion drawn upwardly so as 30 to form a fold of which the lower portion of the rear section is outermost, as plainly seen by reference to Fig. 2, the side edges of the rear section being drawn forwardly around the hips and one of the tabs 19 being utilized to connect the buttons 18 of the 35 rear section at the front, as clearly seen in Fig. 3. The front section 15 is similarly grasped at intermediate points and elevated to form a fold of which the lower portion 40 of the outer section is outermost, as seen particularly in Fig. 4, and the side edges of the thus folded front section are extended rearwardly around the hips, and the buttons 18 thereof connected at the rear by 45 means of the other tab 19, as clearly seen by reference to Fig. 6, it being noted that the forward connected portions of the folded rear section are thereby concealed by the folded front section, as plainly to be 50 seen from Fig. 5, and that by virtue of the connecting webs 20 before described which are positioned at the hips of the wearer, the lapping fold of the front sections forms a 55 pocket across the front, which may be utilized for the reception and retention of clothes pins and other articles.

It is also to be observed from Figs. 5 and 6 that with the front and rear sections of the skirt folded and connected in folded 60 positions around the hips, as described, the bloomers 23 are exposed and the limbs of the wearer may be freely used as desirable in house-work, gardening, sports and the like, the skirt being releasable to extended 65 position by simply disconnecting the tabs 19

of first the folded front section, and then the folded rear section, and then reconnecting the tabs with the skirt sections in extended position, as seen in Fig. 1.

From Figs. 10 and 11 it will be noted 70 that for strength the front and rear sections of the garment have their lower and side edges below the buttons 19 hemmed, as seen at 24, and are provided with stitched transversely extending reinforced tapes 25, 75 which reinforce the intermediate portions of the front and rear sections and serve at their ends to firmly support the buttons 18, the front section 15 having its reinforcing tape 25 preferably provided with a centrally located water proof apron 26 detachably connected thereto by glove or other fasteners 27, which apron will be entirely concealed when the garment is in either the extended or the folded position. 80

I claim:—

1. A garment of the character described including a skirt having side slits extending upwardly from its lower edge and forming front and rear sections, provided with 90 fastening members at opposite sides of the said slits intermediate the ends of the latter, the front and rear sections being independently foldable upwardly and extendible around the upper portion of the skirt in 95 overlapping relation, and tabs having means to engage the said fastening members and arranged and adapted to normally bridge the slits and connect the front and rear sections and to connect the adjacent portions 100 of each of the sections in their folded positions.

2. A garment of the character described, including a skirt portion having vertically extending side slits forming front and rear 105 sections, the lower portions of which are independent of one another, said sections being independently foldable in a vertical direction and arranged to extend substantially around the upper portion of the skirt 110 in their folded position with one folded section overlapping the other folded section, and means for connecting the lower portions of the front and rear sections in their extended position, said means being adapted 115 to connect the adjacent portions of each of the sections in their folded positions.

3. A garment of the character described, including a skirt portion having vertically extending side slits forming front and rear sections, the sections having on their inner faces a distance from their lower ends transverse tapes, said sections being independently foldable in a vertical direction 120 and arranged to extend substantially around the upper portion of the skirt in their folded position with one folded section overlapping the other folded section, and means for connecting the lower portions of the front and rear sections in their extended position, said 125 130

means being adapted to connect the adjacent portions of each of the sections in their folded positions, and including buttons carried by the skirt sections, and tabs having 5 means to engage said buttons in both the extended and folded positions.

4. A garment of the character described including a skirt having side slits extending upwardly from the lower edges thereof 10 and forming front and rear sections provided at their adjacent side edges with fastening means intermediate the ends of the slits and at the ends of the slits with trian-

gular webs, each of said sections being foldable in a vertical direction with its lower 15 portion outermost and being extendible around the upper portion of the skirt in overlapping relation with the side edges of each of the sections adjacent to one another, the said fastening means serving to connect 20 the sections in both the extended and folded positions, whereby the lapping fold of the front section forms a pocket at the front of the garment.

HANS LUDWIG OCHSNER.
